UNITED STATES PATENT OFFICE.

GEORGE M. HARSH, OF BALTIMORE, MARYLAND.

GARMENT-FASTENING LOOP AND METHOD.

Application filed September 6, 1924. Serial No. 736,231.

To all whom it may concern:

Be it known that I, GEORGE M. HARSH, a citizen of the United States of America, residing in the city of Baltimore, State of Maryland, have invented certain new and useful Improvements in Garment-Fastening Loops and Methods, of which the following is a specification.

In the manufacture of pajamas and similar garments, the frogs or loops which ordinarily take the place of regular buttonholes, are made of a special knitted or woven braid particularly adapted for this purpose, but noticeably different in appearance from the garment fabric, the braid which is used being particularly adapted to the formation of a loop which will lie flat and not kink when laundered, the special braid being superior in this way to any loops heretofore made of the garment fabric.

Loops made of this special braid are considered detrimental to the appearance of the highest quality garments, and the present invention relates to a loop or plain woven fabric which may be and preferably is like the fabric of which the body of the garment is constructed, the scraps left in cutting the garment being conveniently utilized.

In the construction of such a loop, one of the difficulties encountered consists in the necessity for so constructing the loops or frogs that they can easily be laundered flat and will lie flat when laundered. To this end the woven fabric, like that of which the body of the garment is constructed, is cut in strips, preferably on the bias, and each strip is folded longitudinally and sewed together as to the edges to form a tube.

An important feature of the invention consists in the formation of the tube with a cord or similar tension member enclosed therein, and extending along one edge of the tube, which tube as an essential of the use to which it is applied, is flat, the sewing or seam being at one edge and the cord or tension member at the other edge of the flat tube. To maintain this arrangement, particularly the placing of the cord or tension member, the edge portions of the material are turned in to a width slightly less than the width of the tube and are caused to bear against the cord, and are sewed in position as the seam at the edge of the tube is formed with their extreme edges bearing against the cord and holding it in position along the edge of the flat tubing opposite

to the seam. This placing of the cord and the arrangement of the edges of the tube also applies a certain additional friction to the cord, tending to limit the freedom with which it slides through the tube, so that when the cord is pulled relatively to the tube, the latter is bent or curved with the cord on the inner or short arc of the curve, the tube still tending to remain flat without kinking. When thus bent or curved by the application of tension to the cord, the tube is most easily and conveniently curved and bent in the form of the desired frog or loop, and when thus curved or bent to form the loops or frogs and sewed, the loops or frogs remain flat and are easily and conveniently laundered flat and retain this position subsequently in use.

In the accompanying drawing I have illustrated a pajama loop or frog constructed in accordance with my invention in two forms and the various stages of manufacturing the same in accordance with my invention.

In the drawing—

Figure 1 is an enlarged perspective view of a short section of fabric tubing with the cord arranged and constructed in accordance with my invention and shown on a somewhat enlarged scale.

Figure 2 is a plan of a longer section of tubing, actual size.

Figure 3 shows the tubing and cord when the cord has been drawn, to curve or bow the tubing.

Figure 4 is a plan of a loop or frog constructed in accordance with my invention in one form; and

Figure 5 is a plan of a loop or frog of a little different form or pattern also made in accordance with my invention.

Referring to the drawings by numerals, the tubing or tape 1 of which the pajama loops 2 and 3 or the like are made, consists of a strip of the fabric of which the garment is made, preferably cut on the bias, as shown in Figure 1, and measuring in width a little less than four times the width of the finished tube when flattened, and a cord or other tension member 4 placed and secured in one edge of the tube as hereinafter described.

In the manufacture of the tube, the lateral edge portions 5 and 6 of the strip, of a width a little less than the width of the tubing when flattened, are folded inwardly forming creases 7 and 8, and the entire strip is folded

over about its centre, turning the edges 5 and 6 inwardly and enclosing the cord 4 which is held in the side of the tubing remote from the folds 7, 8 by the side edges 5 and 6 which bear against the cord. The tube is then completed by stitching the material along the creases 7, 8 on the side remote from the cord, forming a seam 9, thus bringing the creased portions together 10 by sewing through the four thicknesses of the material. This operation may, if desired, be performed by means of a simple type of folder which turns the edge portions 5 and 6 inwardly, forming the creases 15 7 and 8, and turns the material at 10 about the cord, bringing the creases together and the edges 5 and 6 into contact with the cord, and presents the material thus folded to the sewing machine for the formation of the 20 seam 9 practically in a single operation.

The next step of the process consists in cutting the tubes and cord into lengths each suitable to the formation of a frog and pulling or drawing the cord 9 relatively to the 25 end 11 of the tubing, from which it protrudes, forming the material into a bow, which operation, as illustrated in Figure 3, may be accomplished without kinking or 30 puckering or otherwise defacing the tubing which on account of the manner of construction and the placing of the cord therein, remains flat in the plane of curvature, i. e., in the plane of the loop.

The next step consists in curling the material thus bowed as in Figure 3, to form the loops or frogs 2, 3, shown in Figures 4 and 5. This is easily accomplished with the bowed 35 material, curling the same in the direction of the already existing curve, forming a frog or loop which is flat in the first instance and launders flat and remains flat without difficulty.

The frogs or loops may be thus produced of the same material as that of the body of the garment. So made they are inconspicuous, unnoticeable and desirable for the higher quality garment, giving the garment a uniformity of color and shade which is most attractive.

I have thus described specifically and in detail a piece of fabric tubing and a pajama loop or frog made in accordance with my invention from the said tubing, and the method of making tubing and frogs for pajama fastenings and the like in accordance with my invention, the description being specific and in detail in order that the nature and operation of the same may be clearly understood; however, the specific terms herein are used descriptively rather than in a limiting sense, the scope of the invention being defined in the claims.

What I claim and desire to secure by Letters Patent is:

1. The method of making pajama loops

and the like which consists in folding a strip of fabric about a tension member, placing the tension member in one edge of the tube, sewing to form a flattened tape, drawing the tension member to bow the tape in the plane of its flat surface, and forming a loop of the tape thus bowed by curling the tape and sewing the ends and overlapping portions together.

2. The method of making tape for garment fastenings of woven fabric and cord, which consists in forming a strip of fabric, folding the same about a cord, turning the edges in and causing them to bear against the cord, and creasing the fabric at the turn, bringing the creases together and sewing the fabric longitudinally adjacent the creases.

3. The method of making loops for garment fastenings, which consists in forming a strip of fabric, folding the same about a cord, the fold and the cord running longitudinally of the strip, turning the edges in and causing them to bear again the cord, sewing the folds of the fabric formed by turning in the edges, together longitudinally, and curling the tape thus constructed to form loops.

4. The method of making loops for garment fastenings of woven fabric and a tension member which consists in forming a strip of fabric, folding the same about the tension member, turning the edges in and causing them to bear against the tension member, sewing the fabric longitudinally through the four thicknesses including the turned in portions, pulling the cord to bow the tubing, curling it and sewing the contacting portions to form loops.

5. A garment fastening in the form of a loop consisting of a tube of fabric the tube being flat in the plane of the loop and having a separate tension member inside the tube extending longitudinally of the tube and following the inside of the curve of the loop.

6. A garment fastening in the form of a loop consisting of a tube of fabric the tube being flat in the plane of the loop and having a cord inside the tube extending longitudinally of the tube and following the inside of the curve of the loop, the fabric being cut on the bias so that the warp and weft extend at acute angles to the length of the tube.

7. The method of making a loop for a garment fastening from fabric and a tension member which consists in cutting a strip of fabric on the bias, folding the strip about the tension member with the threads at an acute angle to the direction of the tension member, sewing the fabric, pulling the tension member to curve the strip, curling the strip to form loops and fastening at the intersections.

8. The method of making a loop for a garment fastening from fabric and a ten-

sion member which consists in cutting a strip of fabric on the bias, folding the strip about the tension member with the threads at an acute angle to the direction of the tension member, turning the edges of the fabric in toward the tension member, sewing the fabric through the four thicknesses of the fabric thus formed, pulling the tension member to curve the strip, curling the strip to

form loops and fastening at the intersections. 10

Signed by me at Baltimore, Maryland,
this 2nd day of September, 1924.
